UNITED STATES PATENT OFFICE.

CHARLES W. KINNEY, OF GOULDSBORO, PENNSYLVANIA, ASSIGNOR OF ONE-HALF TO
JAMES KINNEY, OF GOULDSBORO, PENNSYLVANIA.

SELF-LEVELING FLOOR.

1,101,451.

Specification of Letters Patent. Patented June 23, 1914.

Application filed April 9, 1912. Serial No. 689,607.

To all whom it may concern:

Be it known that I, CHARLES W. KINNEY, a citizen of the United States, residing at Gouldsboro, in the county of Wayne and State of Pennsylvania, have invented new and useful Improvements in Self-Leveling Floors, of which the following is a specification.

An object of the invention is to provide a self leveling floor, particularly adapted for use on sea going vessels.

The invention embodies, among other features, a floor mounted so as to be self leveling and which is arranged to form a part or continuation of the usual floor of a vessel, the self leveling floor being arranged so that no matter how the vessel may be tilted or careened by a wave, the floor will, at all times, lie in a horizontal plane.

In the further disclosure of the invention reference is to be had to the accompanying drawings constituting a part of this specification in which similar characters of reference denote corresponding parts in all the views, and in which:

Figure 1 is a fragmentary vertical sectional view taken through a vessel, showing the arrangement and construction of the self leveling floor; Fig. 2 is a plan view; Fig. 3 is a horizontal sectional view taken on the line 3—3 in Fig. 1; and Fig. 4 is a horizontal sectional view taken on the line 4—4 in Fig. 1.

Referring more particularly to the views, an opening 10 is provided in the usual stationary floor 11 of a vessel 12, the mentioned floor 11, at the opening 10, being formed with downwardly curved walls 13 so that the opening 10 will be dished in shape. Loosely mounted in grooves 14 formed in the walls 13 are ball bearings 15, formed by mounting a series of smooth faced balls in the grooves 14, the mentioned ball bearings 15 being arranged in diametrical relation to the curved walls 13 and forming a seat 16 for a floor body 17 mounted in the opening 10, the upper surface 18 of the floor body being adapted to normally lie in the horizontal plane of the floor 11. Secured to the under side of the floor body 17 is a weight 19, the said weight depending through an opening 20 formed in the lower portion of the walls 13, a series of apertures 21 being formed in the weight 19 to receive auxiliary weights 22, said auxiliary weights

being removable from the weight 19 for the purpose of increasing or decreasing the stability of the floor body 17. The mentioned floor body 17 is preferably provided with a chamber 23, and a stairway 24 is formed in the floor body 17 and extends from the chamber 23 to the surface 18, a chamber 25 being formed in the floor body for the purpose of storing various articles of food and the like. If desirable, a suitable dumb waiter 26 can be mounted to extend from the chamber 23 to the surface 18 of the floor body, as shown.

The self leveling floor is adapted to constitute a dining floor for the reception of dining tables and may be inclosed by a suitable rail 27 to constitute a dining room. Now it will be readily seen that if the vessel should lurch or careen due to the action of the waves or elements, the floor body 17 will at all times assume a gravitational position so that the surface 18 thereof will be retained in a horizontal plane regardless of the degree to which the vessel may be careened or lunched, it being readily understood that the auxiliary weights 22 can be added to or removed from the weight 19 to compensate for the lurching of the vessel, thus providing an adjustable means for retaining the floor body in proper position, the mentioned floor body being movably supported by the ball bearings 15 constituting the seat 16 therefor.

It will be understood that various departures can be made from the construction disclosed and described herein without departing from the spirit of the invention and that the scope of the invention is defined in the appended claim.

Having thus described my invention, I claim:

In a self-leveling floor, the combination with a stationary floor surface having an opening and supported by side walls, of curved walls supported in spaced relation to the side walls and extending downwardly from the stationary floor at the formation of the opening therein, to provide a dished depression, the said curved walls terminating in an opening, of a series of ball bearings carried in grooves in the curved walls and arranged in a diametrical relation to form a seat, a semi-spherical floor body supported on the seat and provided with a compartment, the said floor body being freely mov-

able on the said ball bearings, and a weight carried on the under side of the floor body and depending through the opening in the said curved walls to lie between the side walls supporting the floor surface and the said curved walls, the said weight being freely movable with the said floor body when the said floor body moves on the said seat, and arranged centrally with respect to the

said floor body and the said stationary floor surface.

In testimony whereof I affix my signature in presence of two witnesses.

CHARLES W. KINNEY.
